Primary Examiner — T. Chase Nelson

(74) Attorney, Agent, or Firm — Banner & Witcoff, Ltd.

(57) **CLAIM**

The ornamental design for a shoe sole, as shown and described.

DESCRIPTION

FIG. 1 is a front perspective view of a shoe sole showing our new design;

FIG. 2 is a second front perspective view thereof;

FIG. 3 is a side view thereof;

FIG. 4 is a second side view thereof; and,

FIG. 5 is a bottom view thereof.

The broken lines showing the remainder of the shoe are for environmental purposes only and form no part of the claimed design.

1 Claim, 5 Drawing Sheets(56)
